UNITED STATES PATENT OFFICE

CHARLES W. SINCLAIR, OF DETROIT, MICHIGAN, ASSIGNOR TO KELSEY-HAYES WHEEL CORPORATION, OF DETROIT, MICHIGAN, A CORPORATION OF NEW YORK

DESIGN FOR A WHEEL

Application filed December 27, 1932. Serial No. 46,623. Term of patent 14 years.

To all whom it may concern:

Be it known that I, CHARLES W. SINCLAIR, a citizen of the United States of America, residing at Detroit, in the county of Wayne and State of Michigan, have invented a certain new, original, and ornamental Design for a Wheel, of which the following is a specification, reference being had therein to the accompanying drawing forming a part

thereof, in which Figure 1 is a perspective view of a wheel showing my new design; Figure 2 is a front elevation thereof; and Figure 3 is a central section therethrough.

I claim:

The ornamental design for a wheel, substantially as shown.

CHARLES W. SINCLAIR.
